(57) **CLAIM**

The ornamental design for a smart floor lamp, as shown and described.

DESCRIPTION

FIG. 1 is a front, right and top perspective view of a smart floor lamp, showing our new design.

FIG. 2 is a rear, left and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a front, left and top perspective view of the lamp of FIG. 1 in a folded position.

The dash-dash broken lines shown in the drawings are included for the purpose of illustrating portions of the smart floor lamp that form no part of the claimed design.
